CLAIM

The ornamental design for a lip shroud, as shown and described.

DESCRIPTION

FIG. 1 is a right side elevational view of one embodiment of a lip shroud showing our new design; with the left side elevational view being a mirror image thereof;

FIG. 2 is a top plan view thereof;

FIG. 3 is a bottom plan view thereof;

FIG. 4 is a front elevational view thereof;

FIG. 5 is rear elevational view thereof;

FIG. 6 is a right side elevational view of a second embodiment of a lip shroud showing our new design; with the left side elevational view being a mirror image thereof;

FIG. 7 is a top plan view thereof;

FIG. 8 is a bottom plan view thereof;

FIG. 9 is a front elevational view thereof; and,

FIG. 10 is rear elevational view thereof.
